NECKTIE CLASP

Edwin S. Mix, Rochester, N. Y., assignor to Hickok Manufacturing Co. Inc., Rochester, N. Y., a corporation of New York

Application August 28, 1950, Serial No. 181,833

1 Claim. (Cl. 24—49)

1
This invention relates to necktie clasps. The present invention is an improvement on the necktie clasp disclosed in my prior Patent 1,981,740, November 20, 1934.

The necktie clasp disclosed in my aforesaid prior patent consists generally of an elongated front bar, one end of which is reversely bent and the extreme end of the reversely bent end is bifurcated and is provided with spaced ears which are substantially right-angularly disposed with respect to the bent portion and which ears are placed in registry with similar ears on the clasping lever and all of the ears are provided with an opening and into which opening a pin or the like is positioned and held, and a coil spring surrounds a portion of the pin intermediate its ends and serves to maintain the clasping lever normally in engagement with the rear portion of the front bar. It is to be noted that the ears on the reversely bent portion of the front bar are, as aforesaid, at substantially a right angle to the remainder of the bar and that the serrated arcuate gripping flanges on the clasping lever are of such shape and width so that when the clasping lever and the said serrated edges are in engagement with the shirt and a necktie clamped between it and the rear face of the front bar, this clasping lever is out of parallelism with the front bar, and, too, it is to be kept in mind that, in my aforesaid patent, the actual gripping members are of arcuate shape and have their edges serrated. Thus, it will be seen that, in my aforesaid patent, there are four component elements; namely, the front bar, the clasping lever, the spring and the pintle pin that serves as a pivot for the clasping lever.

While the necktie clasp as embodied in my said patent is quite effective in clasping the necktie to the shirt of the wearer, my present necktie clasp, as embodied in this application, has advantages thereover and is more effective in use than the necktie clasp in the said patent. In the present invention, there are only three component elements; namely, the front bar which is reversely bent at one end, a spring and the clamping lever. Additionally, the gripping portion of the clamping lever is such that, when applied to the shirt and the necktie is gripped between the same and the inner face of the front bar, the gripping portion of the clamping lever is in parallelism with the rear face of the front bar. In the present invention, therefore, the pintle pin of my prior patent is entirely eliminated and, in effect, is an integral part of the reversely bent portion of the front bar, and the formation and

2
structural characteristics, therefore, of the present necktie clasp including the new form of clamping lever, therefore, differ from the structural features in the said patent.

5. The elimination of the separate pintle pin and the new formation of the clasping or clamping lever in the present invention is important particularly as regards mode or methods of manufacture and the eliminating of any possibility of 10 disconnection or disassociation of the pintle pin from the clamping lever and, of course, is less expensive to manufacture and assemble. Moreover, the formation of the clamping portion of the 15 clamping lever more effectively grips the shirt and tie and eliminates any possibility of accidental loss of the clasp.

In view of the foregoing, therefore, it is an object of the present invention to provide a necktie clasp that can be relatively inexpensively 20 fabricated and possessing a minimum number of component elements or parts.

Another object of my invention is to provide new structural characteristics forming the pivot- 25 ation of the clamping lever or bar with the front bar of the necktie clasp.

Another object of the invention is to provide 30 a novel formation of clamping bar or lever which, when applied to the shirt and with the tie between the same and the rear face of the front bar, results in disposing the clamping portion of the lever in substantial parallelism with the front bar.

Another object of the invention is to provide 35 a novel clamping lever, the structural character- istics of which impart additional rigidity thereto and simplifies the mode of manufacture and the association of the same with the front bar of the clasp.

A still further object of the invention is to 40 provide a necktie clasp embodying a novel struc- 45 ture acting as a pivotal means for the clamping lever with the front bar of the clasp and wherein this pivotal means is integral with and there is a coaction between the clamping lever and the front bar on which this lever is pivotally mounted.

With the above and other objects in view, the 50 invention consists in the construction and novel combination and arrangement of parts herein- 55 after fully described, illustrated in the accom- 55 panying drawings and pointed out in the claim hereto appended, it being understood that various changes in the form, proportions, and minor details of construction, within the scope of the claim, may be resorted to without departing from

the spirit or sacrificing any of the advantages of the invention.

In the drawings:

Fig. 1 is an exploded perspective view showing the three component elements comprising the necktie clasp;

Fig. 2 is a perspective view of the completed clasp;

Fig. 3 is a horizontal sectional view through the completed clasp and showing the same applied to a shirt and necktie;

Fig. 4 is a rear elevation;

Fig. 5 is an enlarged vertical sectional view taken substantially on the lines 5—5 of Fig. 3 looking in the direction of the arrows;

Fig. 6 is a view showing the clasp applied to the shirt and clasping the necktie;

Fig. 7 is a rear elevational view of a slightly modified variation of the necktie clasp;

Fig. 8 is an enlarged sectional view taken substantially on the lines 8—8 of Fig. 7 looking in the direction of the arrows and showing the shirt and the double plies of a necktie between the clamping lever and the front bar looking in the direction of the arrows;

Fig. 9 is an enlarged sectional view similar to Fig. 8 but taken on the line 9—9 of Fig. 7 looking in the direction of the arrows; and,

Fig. 10 is also an enlarged sectional view similar to Fig. 8 but taken on the line 10—10 of Fig. 7 looking in the direction of the arrows.

Like numerals or characters in the several figures of the drawing all denote the same parts.

The invention will be more readily understood by referring to the drawing in detail wherein, from Fig. 1, it will be seen that the present necktie clasp consists of only three elements, namely, the front bar 9, coil spring 10 and the clamping lever 11.

The front bar 9 may be of any suitable outline but, as here shown, comprises an elongated, substantially rigid bar having one end 12 thereof of reversely bent as at 13. This end 12 of the clamping bar 9 is bifurcated or forked as indicated at 14 and consists of the two separate and distinct arms 15 and 16. Inwardly of these arms and also inwardly of the extreme ends 17 thereof, there are opposed, similarly formed projections 18 which projections are flat and of substantially the same thickness as the thickness of the bifurcated end of the front bar. The arms 15 and 16, before the clamping lever 11 and the spring are attached thereto, are spread apart but it will be noted that the projections 18 are in the same plane as the reversely bent portion of the back bar and these projections serve as a pivot means for the clamping lever 11.

The clamping lever is also elongated but preferably of less length than the overall length of the front bar of the completed clasp. This clamping lever 11 is substantially U-shaped in cross section throughout and there is a flange 19 that may be said to extend around or is formed as part of the clasp. The flange 19, on one portion thereof, is scalloped or serrated or otherwise roughened as indicated at 20 and this scalloped formation extends around the extreme end 21 thereof and terminates on both sides of the lever as at 22 and the flange at this point is inclined inwardly somewhat so that it, in cross section, is of substantially the same contour as the cross section of the extreme reduced serrated end of the lever. The flange 19 is somewhat increased in height as at 23 and, at this portion thereof, registered openings 24 are formed there-

in, and rearwardly of these openings, the flange decreases in height as at 25 and, at the end 26, the flange is substantially cup-shaped on its underside and the flat portion 27 thereof serves as a means for allowing one of the fingers of the hand to engage and depress same to move the lever away from the front bar.

It will be seen from Figs. 3, 4 and 5, that the coil spring 10 is positioned about the projections 18 which are brought together and enter the registered openings 24 in the clamping lever, the spring being disposed between the flange on both sides of the clamping lever as clearly shown in Fig. 5 which is on an enlarged scale to show this detail, and the position of the projections 18 when the clasp is completed.

The free ends 28 and 29 of the spring 10 engage respectively in a shallow recess 30 in the reversely bent portion of the front bar 9 and, within the recess created by the said flange on the clamping lever as clearly shown in Fig. 3. Thus, the spring, when engaged about the brought-together projections 18, exerts its motive force to normally move and engage the clamping portion of the clamping lever toward and against the rear face 31 of the front bar 9. It will be noted from Fig. 4 that, when the reversely bent portion of the front bar 9 is in engagement with the clamping lever 11 or vice versa, that the width of the reversely bent portion is of substantially the same width as the front bar 9 or the rear face 31 thereof and, further, that the width of the clamping lever 11 is preferably slightly less than the width of the front bar 9. Further, as will be seen from Fig. 3, when the portion of the shirt S and the necktie denoted at N, in Fig. 3, is disposed between the inner face 31 and the clamping portion of the clamping lever, this clamping portion of the clamping lever is in substantial parallelism with the inner face 31 of the front bar 9 and thus the necktie clasp, when applied, is less bulky than the prior art clasp and this particular structure of the clamping lever makes for a more compact arrangement of the component elements.

In the modified form of the invention, as shown in Figs. 8, 9 and 10 of the drawing, all of the aforementioned characteristics of the invention depicted in the other figures of the drawing are present except that in Figs. 8, 9 and 10 the width 50 of the major portion of the serrated portion of the clamping lever 11 is greater than the cross sectional width of the front bar 9^a and that the end portions from the lines 10—10 and 9—9 outwardly of each is of less cross sectional width 55 than the cross sectional width of the front bar 9^a. In utilizing the front bar 9^a and as will be seen from Fig. 8, the flange 19 extends beyond the opposite side edges thereof except for the ends of the flange 19 where the lines 10—10 and 9—9 are positioned and from Figs. 9 and 10 it will be seen that these end portions of the serrated part of the clamping lever 11 is of less width than the cross sectional width of the front bar 9^a. Thus, the clamping portion of the clamping lever 11 will have a tendency to slightly depress the portions of the necktie N and the shirt S into the hollow or U-shaped interior 32 of the clamping portion 33 of the clamping lever 11 and the end portions 34 and 35 will simply urge or press the portions of the necktie and shirt therebetween toward the inner face 31^a of the narrowed front bar 9^a.

In both modifications of the invention, the 75 clamping portion of the clamping lever when the

clasp is applied to the shirt and is gripping the necktie, will be in substantially parallelism with the front bar or rather the rear face 31 of the front bar.

From the foregoing, it will be seen that in the present necktie clasp, there is indeed a minimum number of parts and the fact that the projections 18 are integral with the reversely bent portion of the front bar and serves as the pivot means for the clamping lever 11, negatives any possibility of accidental disconnection of the pivotal means between the reversely bent portion of the front bar and the clamping lever or vice versa. Then, too, in the manufacture and assembly of the three component elements comprising the present invention, it will be seen that this is readily accomplished in that the bifurcated or forked end of the front bar that is reversely bent is simply brought into position with the opposed projections 18 in alignment with the openings 24 in the clamping lever and the bifurcated portion pressed together with the projections extending through the said openings and substantially abutting when fully engaged therein and providing the point of pivot and the mounting for the coil spring 10 thereon.

The front bar 9 may be substantially flat and elongated, as disclosed, or may be embellished with any desired ornamentation and may have mounted thereon suitable letters or other indicia and may be of substantially the same cross sectional width as the clamping lever or of greater or less width, as desired.

What is claimed is:

A necktie clasp comprising an elongated substantially flat front bar having at one end a reversely bent portion spaced from the rear face thereof, an elongated rigid clamping lever, said lever from a point substantially centrally of its ends, being of partially circular cross sectional shape and gradually tapering to a point at its forward end, the opposite side marginal edge portions of said forwardly tapering part converging to the forward end of the lever and being uninterruptedly serrated and forming fabric gripping portions of substantial length extending in a common plane, the serrated forwardly converging fabric gripping portions being of greatest width at their inner ends and gradually

decreasing in width toward the forward end of the lever, the extreme forward end portion of the lever being curved laterally to the rear side thereof so that the pointed end of the same is

- 5 disposed in the same plane as the serrations of said fabric gripping portions and forms a continuation thereof, that part of the clamping lever rearwardly of said opposed serrated fabric gripping portions being of less width than said 10 forward tapering part of the lever and being of substantially U-shaped cross section, said rear part being formed slightly convex longitudinally at its outer side and being offset laterally and rearwardly from, and extending at an obtuse 15 angle to the plane of said opposed serrated fabric gripping portions, opposite side portions of said narrower rear part of the clamping lever intermediate the ends of said rear part being provided with registered openings therein, means 20 engaging said openings pivotally connecting the clamping lever to the outer free end of the reversely bent end portion of the front bar, whereby when portions of a shirt and necktie are gripped between the forwardly converging 25 serrated fabric gripping portions of the clamping lever and the rear face of the front bar, said serrated portions of the clamping lever will extend in substantial parallelism with the front bar, and the shirt and necktie will be gripped over a substantial area thereof by said parts, the lever also having at its rear end a finger engaging portion disposed opposite to and normally spaced from the reversely bent end portion of the front bar, and a spring carried by said 30 pivot means and normally urging said fabric gripping portions of the clamping lever toward the front bar.
